WINDOW SCREEN HANGER

Albert Lang, Berkeley, Calif.

Application March 27, 1937, Serial No. 133,369

7 Claims. (Cl. 156—14)

The present invention relates to window screens, and more particularly to a new and novel construction and hanging means for screens of the type which are applied to a window frame 5 externally of the window sashes thereof.

An object of the invention is to provide a screen frame constructed entirely of metal, which can be assembled at the factory and to which a hanging means may be easily and conveniently attached in the field where the screen is to be installed.

Another object of the invention is to provide a novel form of hanging means for window screens of the type which are mounted on the outside of a window frame, by which the screen may be hung upon the window frame from the inside of the window frame.

Another object of the invention is to provide a hanging means for a metallic frame of the character described, which can be adjusted from the inside of the window frame after the screen has been positioned thereupon.

Another object of the invention is to provide a simple and practical form of hanging bracket 25 for a window screen, which may be easily and conveniently attached to the screen frame when the screen is being installed upon a window frame.

Another object of the invention is to provide a new and novel form of hanging and securing means for a metallic screen, by means of which the screen may be installed and secured by an operator from the inside of the window frame.

Another object of the invention is to provide a new and novel screen and hanger combination 35 that will permit shipment of the parts in disassembled relation and which can be later assembled in the field in a simple and convenient manner.

Another object of the invention is to provide a 40 novel form of hanger for metallic window screens, of the type having a removable screen fabric, which can be conveniently removed from the screen frame to facilitate a renewal of the screen fabric.

Other objects and advantages of the invention 45 will be in part evident to those skilled in the art, and in part specifically pointed out herein-after in connection with the accompanying drawings, wherein there is shown, by way of illustration and not of limitation, several preferred embodiments thereof.

For a better understanding of the invention reference should be had to the accompanying drawings, wherein;

55. Figure 1 is a fragmentary vertical view of the

outside of a window frame with a screen attached thereto,

Figure 2 is a sectional view taken along line II—II of Figure 1, looking in direction of arrows,

Figure 3 is a fragmentary perspective view 5 taken at the corner of a window frame with a supporting bracket constructed in accordance with the invention secured thereupon,

Figure 4 is a fragmentary perspective view of the corner of a screen frame showing a hanger 10 of the type adapted to cooperate with the bracket shown in Figure 3 of the drawings,

Figure 5 is a fragmentary perspective view of the opposite upper corner of a screen showing the manner of attaching the hanger, illustrated in 15 Figure 4, to the window screen,

Figures 6, 7, 8 and 9 show preferred forms of securing means provided at the bottom of the screen frame in accordance with this invention,

Figure 10 is a fragmentary perspective view 20 showing a modified form of hanger applied to a screen frame,

Figure 11 is a perspective view of the hanger shown in Figure 10,

Figure 12 is a further modified form of hanger 25 illustrating the manner of securing same to a screen frame,

Figures 13 and 14 are respectively plane and perspective, fragmentary views showing a further modified form of the screen hanger and means 30 of attaching same to a window frame,

Figure 15 is a fragmentary sectional view showing a modified form of adjustable bracket for a window screen, and

Figure 16 is a perspective view of the adjustable screen hanger illustrated in Figure 15 of the drawings.

The screen mounting and securing means, contemplated by the present invention, is particularly adapted to screens of the type illustrated and described in my copending applications, Serial No. 75,133 and Serial No. 75,134, filed April 18, 1936, and entitled respectively Window screen, and metal screen and method of manufacture. Therefore to illustrate the present invention there is 40 shown in the drawings, a screen having the characteristics of the frames shown in said prior applications. It is to be understood, however, that the present invention is equally applicable to many other types of screens.

In the past, where outside screens have been applied to a window frame, it has, so far as the applicant is aware, always been necessary to secure the screen upon the window frame at the outside thereof, and as a result the use of a ladder 55

is necessary, particularly where the windows are above the first floor.

To overcome the above objection, the present invention provides a new and novel form of supporting means for an outside screen which will permit a mounting and a securing of the screen, and also a perfect adjustment thereof upon the window frame by an operator at the inside of the window frame.

10 As shown in Figures 1 and 2 of the drawings, the invention contemplates the provision of outwardly extending brackets 10 at each side of the window frame near the upper corners thereof, and a pair of outwardly disposed bracket engaging supports 11 at the upper corners of a screen frame 12 which carries a spline secured screen fabric 13.

As illustrated in Figure 3 of the drawings, the brackets 10 have a flange 14 by means of which 20 they may be adjustably secured upon a sash retaining strip 15 or other portion of the window frame, and disposed in spaced relation and extending out of the window opening, the brackets 10 have a support engaging portion 16 with an 25 upstanding end 17 over which the supports 11 upon the screen frame 12 are adapted to be hooked.

As shown in Figure 4 of the drawings, the bracket engaging supports 11 have a right-angled 30 portion 18 with a slot 19 through which the upstanding end 17 of the bracket 10 is adapted to project. In this latter figure of the drawings, and as is further illustrated in Figure 5, the screen frame 12 is shown as recessed between the 35 points 23 and 24 for a depth equal to the thickness of the bracket 10, so that the screen frame 12 will rest flat against the sash securing strip 15 when the screen is positioned within the recess formed thereby in the window frame.

40 In order to insure a tight fit between the screen frame and the sash securing strip 15 of the window frame, the upstanding portion 17 of the bracket 10 is disposed at a distance A from the surface of the sash retaining strip 15, as shown, 45 which is equal to a distance B, which is the dimension from the inside surface of the screen frame 12 and the outside surface of the right-angled portion 18 of the bracket engaging hanger 11. To provide for the proper vertical positioning 50 of the screen within the window frame opening, the bracket 10 also has a horizontal surface 22 which is disposed a distance C below the upper limit of the screen receiving recess of the window frame, and the upper end of the slot 19 of the bracket engaging hanger 11 is positioned 55 a distance D below the upper outer edge of the screen frame, which distance D is equal to the distance C. With this general form of bracket and bracket engaging support, it will be seen that 60 the screen 13 and its frame 12 may be projected edgewise through the window opening and then with the screen in its outswung position, the bracket engaging supports 11 may be placed upon the brackets 10 by an operator from within the 65 window opening, after which the screen and its frame 12 may be permitted to pivot down and into its normal vertical position within the window opening, as shown in Figure 2 of the drawings.

70 To provide for a vertical adjustment of the screen within the window opening after the screen is in place, and particularly to insure a close fit along the bottom edge thereof with the sill of the window opening, the brackets 10 are made so that 75 they can be adjusted vertically within the window

opening. This adjustment in its simplest form is provided for by a slot 23 in the strip engaging flange 14 through which a securing screw 24 is passed. This slot and screw arrangement, as will be readily seen, will permit the brackets 10 to be adjusted from the inside of the screen, and after the screen has been positioned upon the brackets 10. After the brackets 10 have been properly adjusted, so as to produce the desired positioning of the screen within the window opening, the screw 24 is tightened upon the bracket 10 and an additional screw 25 is then applied to further secure the bracket 10 against any further vertical movement in the window opening.

10 In the manufacture of metallic window screens of the character described, it is particularly important that the assembly of parts be reduced to the simplest form, and for convenience and safety in shipment it is desirable that the screen frames be shipped without the bracket engaging supports or other securing means, as these supports, because of their nature and projection from the screen frame, easily become bent or otherwise damaged. Therefore the bracket engaging supports are constructed in accordance with the present invention so that they may be shipped separately and then easily and readily applied to the screen frame 12 in a simple manner and without special tools by an operator at the point where the screens are to be used. A number of types 15 of bracket engaging supports and means for attaching same to the screen frame 12 will be described in detail hereinafter.

20 As shown in Figure 5 of the drawings, the bracket engaging support 11 is attached to the 25 side of the screen frame 12 by means of a tongue 26 which projects into the side of the screen frame 12, and a screw 27 which projects into the corner of the screen frame channel at the point where a screen securing spline will not interfere 30 therewith. In this particular embodiment of the invention, the screen frame 12 has a flange 28 which is turned back over the outside of the support 11 at the edge of the recessed portion 20-21 upon the inner face of the screen frame 12.

35 Before passing on to a description of the other forms of bracket engaging hangers and modes of adjustment, contemplated by this invention, reference is now made to Figures 6, 7, 8 and 9 of the drawings, which show various cooperating means 40 for securing the bottom of the screen frame 12 within the window opening. Like the brackets 10, all of these securing means are so constructed and arranged as to be effectively applied in securing the window screen by an operator at the 45 inside of the window opening, and therefore, as has been pointed out above, it is possible with the supporting brackets and hangers described, and with the securing means to be now described, to 50 place and secure the screen upon the outside of a window frame from within the window opening.

55 As shown in Figure 6 of the drawings, this securing means comprises a hook-like member 29 which is hooked around an outwardly extending flange 30 upon the screen frame 12, and is retained in a screen locking position by means of an upstanding abutment 31 which is secured upon the window sash by means of a screw 32. The outer hooked end of the member 29 is passed 60 through a groove or notch cut in the outside edge 65 of the flange 30. This form of securing means permits a convenient unlatching of the screen, so that it may be readily removed from the inside of the window opening when required.

70 As shown in Figure 7 of the drawings, the 75

screen frame 12 is shown as secured at its bottom by means of a flanged plate 33 which is likewise secured upon the sill inside of the screen by means of a screw 34. In this arrangement 5 the flanged plate 33 has an upstanding end 35 which is insertable through a groove formed in the bottom of the flange 30 upon the screen frame 12. With this arrangement it will be readily seen that the screw 34 may be removed and applied 10 by an operator at the inside of the window screen.

In Figures 8 and 9 of the drawings, there is shown a further modified form of screen securing means that employs an ordinary hook and eye, and which can be readily applied to the 15 screen and sash by an operator, without special tools, at the location where the screen is being installed. In accordance with this embodiment of the invention, the flange 30 of the screen frame 12 has a slot 36 through which a member 37 extends, the member 37 having extending ears 38 at its outer edge to prevent its being pulled through the slot 36. At the inside of the screen 20 the member 37 is provided with a hole 39 through which the eye of a hook 40 is looped. With this arrangement the parts may be readily disassembled by disengaging the hook 40 from the member 37, which can then be removed from the flange 30 of the screen frame 12. In assembling 25 the parts, the above operations will be reversed, after which the eye of the hook 40 may be bent closed.

As shown in Figure 9 of the drawings, the hook 40 is adapted to cooperate with an eye 41 upon the window frame sill, where the hook 40 is 30 accessible to an operator at the inside of the screen.

Since it is the purpose of the present invention to provide a screen supporting means which is simple in construction, inexpensive to manufacture, and one which can be readily applied to a screen in the field without the use of special tools, resort is had to various arrangements of interlocking tongues and slots. In some of these arrangements the tongues are adapted to be 40 bent into their final positions, and in others the tongues are pre-formed so that they will readily engage cooperating slots formed in the screen frame. Several additional modifications of the 45 screen supporting means constructed in accordance with the present invention, will now be described in connection with the remaining figures of the drawings.

In Figures 10 and 11 of the drawings, there is shown a modified form of bracket engaging support, designated by the numeral 42, which is 50 adapted to be readily attached to the side of the screen frame 12 by a tongue and slot arrangement. In the embodiment shown, the support 42 has three inwardly projecting tongues 43 having 55 downwardly depending ends 44. These tongues 43, with their downwardly depending ends 44, are adapted to be projected through correspondingly located slots in the outside wall of the spline receiving channel of the screen frame 12, after which the bracket engaging support 42 is moved downwardly to interlock the 60 downwardly depending ends 44 with the screen frame, where an offset tongue 45 at the top of the support 42 is adapted to engage in a horizontally disposed slot 46 formed in the screen frame, as shown. The tongue 45 may be such that it will snap into the slot 46, when the support 42 is in its final position, or it may be bent 65 in as a separate operation.

70 In Figure 12 of the drawings, there is shown

a bracket engaging support 47 which is adapted to be secured upon the screen frame 12 by means of tongues 48 and 49 formed upon the outer wall of the spline receiving channel of the screen frame 12. In this embodiment of the invention, the tongues 48 and 49 are arranged in line along the outer surface of the screen frame, and at the inside of the screen frame the support 47 is secured by bending back the flange 30 of the screen frame, as indicated at 50 in this figure 10 of the drawings. The tongue 48 passes through a slot 51 in the support 47 and the tongue 49 is disposed in a notch 52 formed along the outside edge of the support 47.

As a further modification of a screen support 15 constructed in accordance with this invention, there is shown in Figures 13 and 14 of the drawings, an arrangement wherein a support 53 is secured upon the outside surface of the screen frame 12. In this arrangement the screen frame 12 is provided with two oppositely and diagonally disposed slots 54 which extend into the opposite walls of the spline receiving channel of the frame 12 at the outer side thereof, and the support 53 is provided with similarly disposed and cooperating reentrant tongues 55 which, by a rotating movement of the support 53, can be placed into 20 interlocking engagement with the slots 54. After the tongues 55 have thus been rotated into engagement with the slots 54, the support 53 is 25 secured against displacement by means of a threaded securing means 56 that extends into the spline channel of the frame 12 at the corner thereof, where the rounded spline, designated by the numeral 57, will not interfere therewith.

In addition to the above various forms of bracket engaging supports, the present invention also contemplates a modified form of securing bracket which, like the bracket 10, provides for an adjustment of the screen within the window opening from a point inside of the screen 30 after the same has been positioned within the window opening. As here shown, this bracket 35 comprises a right-angled member 58 which is secured within the window opening by means of a screw 59 and an outwardly extending adjustable 40 portion 60 which projects outwardly, where it is engageable by a bracket engaging support 61 attached to the outside surface of the screen frame 12. In this arrangement the adjustability 45 of the portion 60 is provided for by a slot 62 in the member 58 through which a screw 63 carried by the member 60 passes. It will here be seen that after the screen support 61 has been 50 engaged upon the outwardly extending portion 60, the latter portion, by a release of the screw 55 63, may be adjusted vertically to permit any 55 desired positioning of the screen frame 12 within the window opening. In connection with this type of adjustable support, it will be understood that the bracket 61 may be attached to the screen 60 frame 12 in one or more of the manners above described, or it may be attached, as shown in Figure 15 of the drawings, by means of screws 64. If the bracket 61 is positioned along the 65 spline receiving channel of the frame 12, it is contemplated that the spline, here designated by the numeral 57, may be flattened or cut away at this point, as at 65, to provide a clearance for the end of the screws 64.

As shown in Figure 16 of the drawings, the 70 bracket engaging support 61 has a horizontally disposed slot 66 which passes over and behind an upwardly curved end 67 of the adjustable member 60.

While I have, for the sake of clearness and 75

in order to disclose the invention so that the same can be readily understood, described and illustrated specific devices and arrangements, I desire to have it understood that this invention is not limited to the specific means disclosed, but may be embodied in other ways that will suggest themselves to persons skilled in the art. It is believed that this invention is new and it is desired to claim it so that all such changes as come within the scope of the appended claims are to be considered as part of this invention.

Having thus described my invention, what I claim and desire to secure by Letters Patent is—

1. In a window screen, the combination of a metallic frame of substantially rectangular construction upon which a screen fabric is supported, a supporting hanger secured upon the outside of said screen frame adjacent each upper corner thereof, said hangers having a readily detachable tongue and slot connection with said frame, and a securing means extending through said supporting hanger into an outer wall of the screen frame and cooperating with said tongue and slot connection for securing said supporting hanger against displacement upon the screen frame.

2. In a window screen, the combination of a metallic screen of open rectangular construction upon which a screen fabric is supported, said metallic frame having a tongue receiving slot at each upper corner thereof, a supporting hanger secured upon the outside of said screen frame adjacent each upper corner thereof, said supporting hanger having a tongue which projects into the tongue receiving slot in the outer wall of the frame to form a detachable tongue and slot connection between the frame and hanger, and a securing means extending through said supporting hanger and into the screen frame and cooperating with said tongue and slot connection to permanently secure the supporting hanger upon the screen frame.

3. In a window screen, the combination of a metallic frame having a continuous channel extending therearound for the reception of the edges of a screen fabric, a screen fabric upon said frame, a metallic spline within said channel for securing the screen fabric upon the frame, said spline being rounded at the corners of the screen to provide a free space within and at the corners of said channel, a supporting hanger secured upon the outsides of the channel of said screen frame adjacent the upper corners thereof, said hanger having a readily detachable tongue and slot connection with said screen frame, and a securing means extending into the free space at the corners of said channel and cooperating with said tongue and slot connection for securing said supporting hanger against detachment from the screen frame.

4. In a window screen, the combination of a metallic frame having a continuous channel extending therearound for the reception of the edges of a screen fabric, a screen fabric upon said frame, a metallic spline within said channel for securing the screen fabric upon the frame, said spline being rounded at the corners of the screen to provide a free space within the channel at its corners, a supporting hanger secured

upon the sides of said screen frame adjacent the upper corners thereof, said hanger having a projecting tongue that projects into a slot in said screen frame, and a threaded securing means cooperating with said tongue for securing said hanger against displacement upon the screen frame.

5. In a window screen, the combination of a metallic frame of rectangular cross section having a continuous channel extending therearound for the reception of the edges of a screen fabric, a screen fabric upon said frame extending at its edges into said channel, a metallic spline of circular cross section within said channel for securing the screen fabric upon said frame, said spline being formed with a rounded bend at the corners of said screen frame to provide a free space within said channel at the corners thereof, said metallic frame having tongue receiving slots extending through the outside wall of said continuous channel adjacent the upper corners of the frame, a screen frame supporting hanger having a projecting tongue adapted to project into the slots at each upper corner of said frame, and a screw threaded means projecting through said supporting hanger and the outer wall of said channel into the free space at the upper corners of said channel adapted to cooperate with the tongues upon the supporting hangers and the slots in said frame to secure said supporting hangers firmly upon said frame.

6. In a window screen, the combination of a metallic frame of rectangular cross section having a continuous channel extending therearound for the reception of the edges of a screen fabric, a screen fabric upon said frame extending at its edges into said channel, a metallic spline of circular cross section within said channel for securing the screen fabric upon said frame, said spline being formed with a rounded bend at the corners of said screen frame to provide a free space within said channel at the corners thereof, said metallic frame having vertically disposed tongue receiving slots extending through the outside walls of said continuous channel adjacent the upper corners of the frame, a screen supporting hanger at each upper corner of the frame having a tongue thereupon adapted to be inserted in the slots of said frame, and means projecting through said supporting hanger and an outer wall of said channel and into the free space at the corners of said channel adapted to cooperate with the tongue upon the supporting hanger and the slot in said frame to secure said supporting hanger firmly upon said frame.

7. In a window screen, the combination of a metallic frame of rectangular cross section having a continuous channel formed in one side thereof for the reception of the edges of a screen fabric and a surface engaging flange around the outer edge of said channel, and a screen hanging support secured upon the outer side wall of the channel of said metallic frame by a tongue and slot connection and a back folding of said flange over an adjacent edge of said screen hanging support.

ALBERT LANG.
